US00D575298S

(12) **United States Design Patent**
Chen et al.

(10) **Patent No.:** **US D575,298 S**
(45) **Date of Patent:** **** Aug. 19, 2008**

(54) **USER INTERFACE FOR TOUCH SCREEN**

(75) Inventors: **Chin-Feng Chen**, Tu-Cheng (TW);
Tay-Yang Lin, Tu-Cheng (TW)

(73) Assignee: **Hon Hai Precision Industry Co., Ltd.**,
Tu-Cheng, Taipei Hsien (TW)

(**) Term: **14 Years**

(21) Appl. No.: **29/269,177**

(22) Filed: **Nov. 21, 2006**

(30) **Foreign Application Priority Data**

Jun. 30, 2006 (CN) 2006 3 0017124

(51) **LOC (8) Cl.** **14-04**

(57) **CLAIM**

The ornamental design for a user interface for touch screen, as shown and described.

DESCRIPTION

The FIGURE is a front view of a user interface for touch screen showing our new design.

The outer rectangle shown in broken line is included for the purpose of illustrating a touch screen and forms no part of the claimed design. The inner rectangle shown in broken line defines the bounds of the claimed design and forms no part thereof.

1 Claim, 1 Drawing Sheet
